UNITED STATES PATENT OFFICE.

NATHAN J. GOLDFARBE, OF NEW YORK, N. Y., ASSIGNOR OF ONE-HALF TO PHILIP RABINOWITZ, OF BROOKLYN, NEW YORK.

PHOTOGRAPHIC-PRINTING APPARATUS.

1,108,744.

Specification of Letters Patent. Patented Aug. 25, 1914.

Application filed July 25, 1913. Serial No. 781,091.

To all whom it may concern:

Be it known that I, NATHAN J. GOLDFARB, a citizen of the United States, residing in New York, borough of Brooklyn, in the county of Kings and State of New York, have invented certain new and useful Improvements in Photographic-Printing Apparatus, of which the following is a specification.

10 This invention relates to photographic printing apparatus of the pivoted or swivel type adapted to be rotated toward and from a source of light by which the printing is effected.

15 The object of the invention is to provide a simple and reliable device of this kind, by which the light is automatically turned on and off at the proper times, and the frame automatically opened when turned away

20 from the light after exposure. These objects are attained by proper arrangement of electric switch devices, and by mechanical releasing means in connection with springs which throw open the back of the frame.

25 The frame is arranged relatively to the light so that the operator is permitted by passing the hand between the frame and the light to hold back the printing of parts of the negative as desired, after the practice of

30 photographers when printing in the usual manner with unmounted printing frames.

In the accompanying drawings, Figure 1 is a perspective view of a device embodying the invention, shown in open position preparatory to receiving a negative and paper for printing, Fig. 2 is a similar perspective showing the frame with its back closed and the parts in position ready for turning the frame into printing position, Fig. 3 is a perspective view showing the device in printing position, Fig. 4 is a vertical section on a larger scale on line 4—4, Fig. 2, Fig. 5 is a side view of one of the frame-standards with parts in section, on line 5—5, Fig. 6, Fig. 6 is a top-view of the frame-standard shown in Fig. 5, also showing the coöperating parts on the printing-frame, Fig. 7 is a vertical section on line 7—7, Fig. 2, and Fig. 8 is a top-view of the other end 50 of the frame, and standard, from those shown in Fig. 6.

Similar reference numerals indicate corresponding parts in all the figures.

The base 70 of the device supports two upright standards 29, 30, of wood or other suitable material, between which the frame 7 is supported on trunnions 28, 32, one at each end of the frame, so that the latter is capable of oscillation on its longitudinal axis between the standards.

Between the frame 7 and standard 29 is supported on trunnion 28 a coil-spring 72, one end of which is secured to the standard and the other to the frame. Said spring tends to turn the printing-frame 7 in direction of the arrow 35, Fig. 3. Movement of the frame in said direction is limited by means of an abutment-pin 22 projecting longitudinally from the end-bar of the printing-frame in such position as to engage the top of the standard and arrest the frame when the latter arrives in discharging position as shown in Figs. 1 and 2. A friction-brake 23 is arranged on the standard 29, said brake comprising a piece of spring-metal extending eccentrically, its upper end outside of the path of the pin 22, and its lower end provided with a seat 71 for the pin in such position as to receive and frictionally engage the pin when the pin approaches the standard. The frame is thus cushioned and retarded in its return movement, so as to avoid shocks, and is, by the pin and socket, retained in position against the ordinary shocks of discharge and refilling.

The back of the printing-frame comprises two leaves, 26, 27, one of which, 27, is hinged to the end-rail of the frame at the end adjacent the standard 30, and the other of which is hinged to the leaf 27. A spring 15 is employed in connection with the hinge 14 between the leaves, which spring has a tendency to open the leaf 26 from the frame 7. The power of the spring is such that when the leaf 26 is released, the spring will not only open said leaf away from the frame, but the momentum will assist in opening the other leaf, 27, which is also provided at its hinge 73 with a spring 16. The combined action of the two springs is sufficient to completely open the back of the frame from closed position to discharging position shown in Fig. 1, in which the back is supported by a rest 10 secured to and projecting above the top of the standard 30.

The discharging position of the printing-frame, in which it is limited by its abutment-pin 22, is a forwardly-inclined position, as shown in the figures, thus enabling 5 the operator who stands in front of the frame to see at substantially right-angles to his line of vision the entire interior of the printing-frame and any negative 44 or paper 79 therein. The rest 10 has its upper edge 10 likewise inclined, whereby the back 26, 27, of the frame is supported on a line transversely of the same. The upper end of the rest 10 is provided with a cushion 4, which is in line with the hinge 14 when the back 15 is swung open, so that the shocks of arresting the opening movement of the back are taken up by said cushion, and the hinge 14 forms a shield abutting therewith and avoiding injury to the leaves 26 and 27.

20 Motion of the printing-frame in direction toward printing-position is limited, in case the frame be moved sufficiently far, by abutment of the pin 22 against the front-portion of the standard 29. It is only necessary, 25 however, to oscillate the frame by hand or by foot-operated mechanism hereinafter described, to a point slightly beyond printing position, in order to permit operation of a pawl 20 which arrests the frame in exact 30 position suitable for printing. Said pawl is pivoted on a horizontal axis by any suitable means to the standard 30 below the axis of the printing-frame, and extends upwardly at the inside of the standard in such 35 position as when advanced to come beneath the rear portion of the frame as shown in dotted lines in Fig. 8. A handle 18 at the other end of the pawl serves for its manual operation. A spring 13 on the horizontal 40 portion of the pawl normally actuates it into the path of the printing-frame. When, therefore, the frame is turned in the direction of the arrow in Fig. 2, from discharging into printing position, the frame moves 45 the pawl 20 laterally, and when past the same the pawl springs into place, and upon the frame now being released, spring 72 returns the frame into contact with the nose of the pawl, where it remains at rest 50 during printing.

When the printing operation is finished, pressure on the handle 18 moves the pawl out of the path of the frame, which then is oscillated by its spring in the direction of arrow 35, Fig. 3, into discharging position.

55 The lamp for printing may comprise a suitable incandescent electric lamp 6, supported at proper distance above the frame 7 by a flexible arm 3, whereby the lamp may 60 be exactly positioned for the best angle relatively to the frame, also its distance therefrom changed by suitable bending of the arm, as required. The arm is secured to the base 70 by any suitable means.

65 Between the standards 29, 30, and below

the frame 7 is supported on the base 70 a ruby or other suitable lamp 5 not affecting the photographic paper, and providing sufficient light for use during the operations of removing the printed sheet from the 70 frame and inserting a fresh sheet for printing.

The automatic turning of the current through the lamps 5 and 6 is effected by contacts 1, 2, on the standard 29, and a co-operating contact 60 on the frame 7, said contacts being suitably connected by wires 74, 75, 76, with the lamps and with a source of electricity. When the frame swings from discharging to printing position it moves 75 contact 60 away from contact 2 and into engagement with contact 1, and thus switches the current from lamp 5 to lamp 6, for printing. When swung in reverse direction, the current is switched from lamp 6 to 80 lamp 5.

The automatic opening of the back of the frame when the frame arrives in discharging-position, after printing, is permitted by means of a release-device comprising a 90 latch-plate 9 pivoted to the printing-frame 7 and having its portion, adjacent the leaf 26, normally in the path of a latch 12 by which the back 26, 27 of the frame is secured closed. The latch 12 consists of a 95 metal spring fastened at one end to the leaf 26, and projecting at its other end upwardly from the leaf and beyond the edge of the same, whereby when the spring is manually depressed below the latch-plate 9 it exerts 100 spring-pressure on the leaf 26, thus yieldably but with sufficient force holding the paper and negative immovable in the printing-frame. A spring 41 actuates the latch-plate so that its edge adjacent the spring 105 12 is normally in the path of the latter when depressed for closing the printing-frame. An inclined guard 47 receives the latch 12 when the latter is depressed, enabling the latter to move the plate around 110 the pivot 40 of the plate, thus permitting the latch to pass. When passed, the spring 41 returns the latch-plate 9 into locking position. Retaining-screws 62, 63 in arcuate slots of the latch-plate, retain and guide 115 the same on the rail of the printing-frame, while permitting it to swing for latching and unlatching. On a suitable pivot 43 at the inside of the standard 29, adjacent the latch-plate 9, is a rotary catch 42, having a 120 tooth 52, projecting into the path of a finger 64 of the latch-plate 9, and having a lug 50 bearing against a stop 51 on the standard. A spring 25 tends to rotate the catch in the direction of the arrow 45 in 125 Fig. 5.

When the printing-frame, after printing, is returning to discharging position, the finger 64 bears against the convex back of the tooth 52 and is moved by the same out- 130

wardly, thereby swinging the latch-plate 9 on its pivot and withdrawing the latch-plate out of the path of latch 12. The latch 12 thus being released, the springs of the back 5 26, 27, open the frame, as before described. Such release takes place a short distance before the arrival of the frame 7 in discharging position. The further movement of the frame brings the finger 64 beyond the tooth 10 52, and spring 44 returns the latch-plate into normal position, shown in Fig. 5. The finger 64 being now below tooth 52, remains in that position, and returns thereto when for closing the printing-frame the latch 12 15 is depressed and the plate moved as described heretofore.

The catch 42 being pivoted eccentrically to the printing-frame, it follows that when, after the frame is filled, it is moved in direction of the arrow 77 in Fig. 2 toward printing position, the finger 64 engages tooth 52 and carries the same along for a short distance, rotating the catch 42, against the tension of spring 25. The paths of the finger 25 and of the tooth gradually diverge, and finally become separated to such an extent that the finger 64 releases the tooth, after having moved only a small part of a complete rotation. The catch 42 is returned by 30 spring 25, into position with its lug 50 arrested against the stop-pin 51, thus placing the catch in position for again tripping the latch when the frame is returned from printing position to discharging position.

35 For operating the frame from discharging position to printing position by the foot of the operator, the frame 7 is provided adjacent the standard 30 with an arcuate block 65 at one end of which is fastened a chain 8 40 or other suitable flexible connecting means, which descends through an opening in the base to a foot-treadle 78 secured to the floor or any suitable point of support. When the treadle is depressed, the chain is lowered, 45 swinging the frame against the tension of its spring 72 in the direction shown by arrow 77 in Fig. 2, from charging position into printing position, where it may be held by the foot of the operator on the treadle, as long 50 as may be desired. In this case, the spring-pawl 20 is not required to be used, and is held out of operation by means of a hook 19 on the standard 30, which is hooked over the handle 18, thus retaining the pawl out of 55 operation.

The freedom of movement of the printing-frame, the automatic control of the lamps, and the automatic opening of the frame after printing, together with the automatic 60 return of the frame from printing to discharging position when released by withdrawing pawl 20, enable the rapid production of prints of high quality. The freedom of movement of the printing lamp to 65 any desired position, also its location above

the frame, and the freedom of the apparatus from any obstruction between the lamp and the frame, permits the operator to hold or pass the hand between the lamp and the frame, during printing, for retarding portions of the print, with the same freedom as with ordinary unmounted printing frames, thus enabling this important method of working in the art to be utilized to its full extent. 75

It is obvious that the invention is not limited to the precise construction shown and described herein, but changes may be made therein without departing from the spirit of the invention as set forth in the claims. 80

I claim:

1. A photographic printing frame, comprising an oscillatory frame, and means automatically operative to open the frame when the latter arrives in a predetermined position. 85

2. A photographic printing apparatus, comprising an oscillatory frame, automatic means for opening the same after printing, and means for oscillating the frame into engagement with said opening means. 90

3. A photographic printing apparatus, comprising an oscillatory frame, a latch and latch-plate normally retaining the same closed, and a catch in the path of the latch-plate, adapted to release the same from the latch at a predetermined point in the oscillation of the frame. 95

4. A photographic printing apparatus, comprising an oscillatory frame, and a source of light at printing distance therefrom, controlled by the oscillation of the frame, there being a free and unobstructed space for hand-retarding of the exposure, between said frame and said source of light. 100

5. A photographic printing apparatus, comprising an oscillatory frame spring-actuated toward open position, and means for arresting the same in printing position against the tension of its spring. 105

6. A photographic printing apparatus, comprising an oscillatory frame spring-actuated toward discharging position, means for limiting the movement of the same when arrived in discharging position, and means for retarding the movement of the frame when approaching discharging position. 110

7. A photographic printing frame, comprising an oscillatory frame, having a back hinged transversely to the axis of the frame and opening toward one end of the same, means at the opposite end of the frame for retaining the back closed, and means for releasing said retaining means at a predetermined point in the rotation of the frame. 120

8. A photographic printing frame, comprising an oscillatory frame, having a back hinged transversely to the axis of the frame and opening toward one end of the same, 130

springs normally opening said back, means at the opposite end of the frame for retaining the back closed, against the tension of said springs, and means for automatically releasing said retaining means.

9. A photographic printing frame, comprising an oscillatory frame spring-actuated from printing position toward discharging position, and manually operable means retaining the frame in printing position.

10. A photographic printing frame, comprising an oscillatory frame, means for limiting the movement of the frame in one direction at one angle toward the source of light, and means for limiting the movement of the frame in the other direction at a different angle to the source of light.

11. A photographic printing frame comprising an oscillatory frame, a printing lamp spaced unobstructedly therefrom in one direction, a ruby lamp spaced therefrom in another direction, and means for oscillating the frame between the lamps.

12. A photographic printing frame comprising an oscillatory frame, a printing lamp spaced therefrom, a ruby lamp spaced therefrom, and electrical switching means controlling said lamps and operable by said frame in its rotation.

13. A photographic printing frame comprising standards spaced apart, a printing frame supported on its longitudinal axis between the standards and spring-actuated toward discharging position, a back hinged to open over one standard, and a rest on

said standard adapted to support said back when the frame is in discharging position.

14. A photographic printing frame comprising standards spaced apart, a printing frame supported on its longitudinal axis 40 between the standards and spring-actuated toward discharging position, a back hinged transversely to the axis of the frame at one end of the frame and spring-actuated toward open position, a catch eccentrically mounted 45 on one of said standards at the opposite end of the frame, a latch-plate pivoted to the frame and adapted to be moved by said catch when approaching discharging position, and to operate said catch for passing 50 the same when moving in the opposite direction, and a latch on said back engaging the latch-plate and adapted to be released when the plate passes over the catch during the movement of the frame toward discharging 55 position.

15. A photographic printing frame comprising an oscillatory frame, flexible motion transmitting means attached thereto for oscillating the same, a foot-treadle attached 60 to said motion-transmitting means, and means for limiting the movement of the printing-frame at printing-position.

In testimony, that I claim the foregoing as my invention, I have signed my name in 65 presence of two subscribing witnesses.

NATHAN J. GOLDFARB.
